MACHINE FOR CURLING HAT BRIMS.

No. 308,758.

Patented Dec. 2, 1884.

UNITED STATES PATENT OFFICE.

RUDOLF EICKEMEYER, OF YONKERS, NEW YORK.

MACHINE FOR CURLING HAT-BRIMS.

SPECIFICATION forming part of Letters Patent No. 308,758, dated December 2, 1884.

Application filed June 24, 1884. (No model.)

To all whom it may concern:

Be it known that I, RUDOLF EICKEMEYER, of Yonkers, in the county of Westchester, in the State of New York, have invented certain new and useful Improvements in Machines for Curling Hat-Brims; and, I do hereby declare that the following specification, taken in connection with the drawings furnished and forming a part thereof, is a clear, true, and complete description of the several features of my invention.

The curling of brims is well known to be an important branch in the manufacture of hats, and the state of the art in said branch prior to my present invention may be fairly indicated, as follows, viz: hand operations involving much manipulation and the use of hand-tools and pressing-irons; also, hand-tools worked upon a special table or bed and with a properly-mounted hat-block, so that the edge of a hat-brim may be progressively turned, folded, and pressed, while the tools are moved peripherally around the brim; also, a somewhat similar organization of bed, block, and tools, but so arranged that said tools remain stationary, while the block with a hat thereon is revolved for progressively presenting the periphery of the brim to said tools. Whether the curling-tools referred to be moved around the hat-brim, or the latter be revolved, and thereby fed to the tools, there is obviously more or less twisting or tangential strain upon the brim, and if the brim chance to be well heated it is liable to be drawn out of shape, and this liability I seek to and do wholly obviate.

Operations with all of the foregoing tools and machines are comparatively slow and quite expensive, because none but highly-skilled workmen can be relied upon in their use. Molds and presses of various kinds have also been devised and used far enough to demonstrate that if anything was thereby saved in the matter of skilled labor it was more than offset by slowness in operation, and also by the cost of molds, of which one was not only required for each style of hat, but also for each size.

With a view to rendering the operation more rapid than was possible with ordinary molds or bag-presses, machines have been heretofore devised containing brim-molds con-

structed in two parts or sections, and provided with means for moving said sections toward and from a brim when interposed between them and a solid mold. So, also, have four similar brim-folding sections been heretofore organized so as to be moved laterally, each into contact with a portion of a hat-brim and forcing it over and upon a central mold.

Types of machines of the two varieties last referred to are shown and described in the United States Letters Patent of Apple, Lindheim, and Baer, dated December 4, 1860, No. 30,791, and of Morlot, dated February 1, 1870, No. 99,458. So far as my knowledge extends, no machines of these last-named varieties have ever been practically applied to use, which can be accounted for, as I have reason to believe, in part because in the one case each of the two sections embraced one-half of the periphery of the brim, and in the other case each of the four sections embraced one-quarter of the periphery, and therefore in neither machine could the edge of a brim be folded in lines at right angles to the periphery of the brim, except at the center of each section; also, in part because in both machines said sections in their separated positions must fail to cover or engage with the entire periphery of the brim, or with a sufficient portion thereof to prevent other portions of the brim from so intervening between the ends of said sections as to cause said portions to protrude upwardly, and to be therefore pinched and crimped when the sections were next forced farther inwardly. This inability of the sections to effectually control the entire periphery of a brim must have subsequently involved much expensive and skillful manipulation for correcting the effects of the unequal draft or pull on the hat-brim, and also at the crimped portions, and in both machines comparatively expensive molds were required for each size and style of hat.

The objects of my invention are to provide for evenly and effectually folding the whole or any lesser portion of the edge of a hat-brim upon itself without the use of molds, and to rapidly enable the operation to be performed by means of mechanism which can be practically operated by persons of ordinary intelligence, however unskilled in the art of brim-curling as heretofore practiced.

In my novel machines I use for the first

time a novel expandible and contractible brim-folding ring, which maintains substantially the same annular continuity when fully expanded that it has when completely contracted, and therefore every portion of it, in moving inwardly, moves over the edge or periphery of a brim in lines substantially at right angles to said periphery, and no portions of said brim can possibly be pinched or crimped out of the shape desired. I also employ means for gagging the width of the brim and determining the peripheral outline of the folded brim; but instead of using a mold in that connection, as heretofore, I employ a cheap flat annular guide-plate, over which the edge of a brim is folded, and of which a single set or series serves not only for all sizes of hats, but also all variations in width of brim, because each plate has a central opening a little larger than the largest-sized hat-crown, and it can therefore be used on any hat having a smaller crown, and so enable a narrow brim to be developed on a large hat or a wide brim on a small hat, because said plates vary only in their peripheral dimensions. With these annular folding guide-plates I also employ a set or series of annular plates, each of which serves as a lifting-plate for enabling the brim-folding ring to properly engage with the edge of a brim, and it also serves as a gage to properly locate the guide-plate upon the brim of a hat, said brim being in turn properly located upon the lifting-plate by a hat-block, which is centrally mounted within said lifting-plate. The interior edge line of each lifting-plate corresponds with the periphery of the guide-plate, but they differ in size, so as to afford an intervening annular space of about one-eighth of an inch, which is about equal to the average thickness of a hat-brim. The brim-folding ring and the hat-block are provided with means whereby the ring is expanded and contracted, and said block and ring are placed into compressing relations, so that a folded brim interposed between said block and guide-ring can be properly pressed for developing a well-defined edge.

After describing in detail a machine embodying my invention, the several novel features and combinations of mechanism will be specified in the several claims hereunto annexed.

Referring to the five sheets of drawings, Figure 1, Sheet 1, is a vertical central section of a machine in which I have embodied all of the features of my invention, said section being on a line from front to rear. The folding-ring is shown in its expanded condition, with the hat-bed lowered and ready to receive a hat-block. Fig. 2, Sheet 2, is a partial front view and lateral vertical central section of the same with the working parts in position, as shown in Fig. 1, but having a hat-block on the bed and a hat on said block, as if ready to commence the curling operation. Fig. 3, Sheet 2, is a top view of an annular cross-head to

which the brim-folding ring is operatively connected. Fig. 4, Sheet 3, is a view like Fig. 1, but with the hat bed and block and a hat fully elevated, the folding-ring fully contracted, and a hat-brim folded or curled. Figs. 5 and 6, Sheet 3, illustrate the brim-folding guide-plate and the brim-lifting plate detached in top view, and also in diametrical section. Fig. 7, Sheet 4, is a sectional view of the upper portion of the machine, differing from the corresponding portion of Fig. 2 only in being enlarged and in showing the brim-folding ring in a partially-contracted condition. Figs. 8 to 13, inclusive, Sheet 4, illustrate in various views detached portions of the machine shown in Fig. 7, fully indicated by corresponding letters of reference. Fig. 14, Sheet 4, is a partial plan and sectional view of the top plate of the machine with a portion of the brim-folding ring in position thereon. Fig. 15, Sheet 4, is an edge view of the lower adjacent portion of Fig. 14. Fig. 16, Sheet 4, is an edge or side view of the top plate of the machine detached. Fig. 17, Sheet 5, is a plan of the under side of the top plate with a portion of the folding-ring attached thereto and in a contracted condition, another portion of said ring being shown in an expanded condition, and parts of said ring are removed to disclose the under surface of the top plate. Figs. 18 to 20, inclusive, are various views of finger-shoes, of which the brim-folding ring is in part composed. Figs. 21 to 23, inclusive, are similar views of finger-plates, which also constitute a portion of the folding-ring when constructed in a specially-desirable manner. Fig. 24 is an edge view of a portion of the brim-folding ring and of the lower portion of the top plate, to which said ring is attached.

The frame A is of a substantial character, including side plates, a, a horizontal middle plate, a', and a top plate, b, of complex construction, illustrated in enlarged detail views on Sheet 4, and it can be best described in connection with Fig. 16, wherein is shown a flat oval cap, b', joined to an oval curved or arched bottom plate, b², by numerous pendent radial webs b³, the whole capable of being cast in one piece or in separate pieces. It is provided with two side ears perforated to receive bolts, by which it is secured to the top of the side plates, a, and also to receive vertical guide-rods, to be hereinafter described. The oval curved bottom plate, b², is radially slotted, and has on its under side an annular oval arched hub, b⁴, which will hereinafter be again referred to in proper connections.

The hat-bed B is mounted upon a central vertically-reciprocating spindle, B', which is connected with a treadle, B², in the manner shown and described in my prior Letters Patent No. 175,953, April 11, 1876, and No. 200,034, February 5, 1878, in connection with machines for stretching and blocking hat-bodies.

Although the treadle B², with the bell-crank

lever B³ and link B⁴, in combination with a hat-supporting spindle, B', constitutes a feature heretofore patented to me, I herein claim the same, in combination with the hat-bed, the 5 brim-folding ring, and its accompanying mechanism, to be hereinafter described, said combination enabling results to be obtained which were impossible with any prior machine devised by me containing said treadle and spindle and their intermediate connecting lever 10 and link. Upon the hat-bed there is an annular oval brim-lifting plate, c, which, like the bed, is arched to correspond with the average curve of a hat-brim from front to rear. 15 This brim-lifting plate is one of a set of thin, cheap, metal plates, varying according to the peripheral dimensions of brims to be curled, and each has a pair of pendent dowel-pins, c', Figs. 5 and 6, which occupy corresponding 20 holes (not shown) in the hat-bed, said holes being so located as to prevent said plate from being improperly set on the bed. The prime function of said plate c is that of a lifting-plate for lifting the edge of a brim, as will be 25 hereinafter described, but it also in one sense serves as a gage-plate for properly locating a brim-folding guide-plate, d, Figs. 5 and 6, which is one of a set of cheap thin plates provided with vertical dowel-pins d', which project 30 from the upper surface and occupy holes d' in the oval annular hub, b⁴, already described. The folding guide-plate d is sufficiently smaller than the lifting-plate to afford an intervening space all around of about one- 35 eighth of an inch, which is about equal to the average thickness of a hat-brim.

On referring to Figs. 5 and 6 it will be seen that the folding guide-plate d and the lifting-ring e are not true ovals, but are what are 40 known as "egg ovals" or "hat ovals," and that therefore it is important that the dowel-pins c' and d' should be respectively so arranged thereon that each of said annular-plates will not only be accurately located with reference to centers, but also with reference to 45 having the small ends of each plate always in their proper position when mounted for service, and therefore said pins in each case are irregularly located, as shown, so that neither 50 annular-plate can possibly be mounted out of its true position, and the same provisions are made in connection with the hat-block e, which has not only a central hole for receiving the spindle B', but also on each side of its center, 55 the holes e', which receive the dowel-pins e'', projecting upward from the hat-bed. In lieu of said irregularly-located dowel pins for the hat-block, I have employed a novel triangular 60 chuck and socket devised by me, which properly centers the hat-block, and also renders it impossible for said block to be mounted on said bed other than in its exactly proper position.

While the folding-ring shown is arranged 65 to co-operate with a lifting-ring, it is to be understood that I do not limit myself thereto,

because I am well aware that said folding-ring can be organized not only to operate also as its own lifting-ring, but also still further as a compressing-ring, and so as to be operative, 70 without the vertically-reciprocating hat-bed, and such a folding-ring has been devised by me, and will constitute in part the subject of a separate application for Letters Patent.

As thus far described it will be readily seen 75 that when a hat, e³, (on a block, e, as shown, and properly mounted upon the hat-bed and block-spindle,) has its brim e⁴ compressed at its upper surface by the folding guide-plate d, that the entire periphery of the brim will be 80 turned upwardly by the aid of the lifting-plate c to a greater or less extent, as indicated in dotted lines in Fig. 6, thus placing said edge readily within the control of the novel brim-folding ring C, so that when said 85 ring is contracted it will fold the edge of the brim inwardly over the edge of the guide-plate d, and flatly upon its upper surface.

This brim-folding ring may be largely varied in construction without departure from certain portions of my invention. I have practically employed these rings variously constructed, and have always obtained good results with such as substantially maintain their 90 annular or ring-like character when in their expanded condition, and which are therefore enabled to evenly fold the edge of a brim without crimping or pinching any of the unfolded portions into ridges, because all of the working-surface of the ring moves in folding at 95 right angles to and across the peripheral line of the brim.

I have employed a ring composed of metallic sections faced with an unbroken elastic ring of vulcanized rubber, and also a ring composed only of simple metallic sections, and I find that the latter will perform as good service as when faced with rubber; but I have obtained very desirable results with a ring composed of complex metallic sections, each 100 of which operates as a folding-finger, so that said ring embodies, in fact, two connected and co-operating series of radially-movable segmental sections. If it should be desired to fold the edge of a truly-circular brim, the ring 105 is made truly circular in form; but the usual outline of hat-brims is a hat oval, and therefore I have illustrated my machine as organized for folding or curling the edges of such oval brims. In order to obtain the results desired, each 110 quarter of the ring must embody a series of sections, and each section must be movable in radial lines, and if the ring be circular the said lines of movement will radiate from a single central point; but if the ring be oval, 115 said lines will radiate from two or more interior central points.

The construction of the folding-ring can be best described in connection with Figs. 14 and 15, Sheet 4, and the several figures on Sheet 120 130 5. As before stated, good results will accrue by the use of simple radially-movable sections;

but in that case a large number thereof should be employed, each being in a general way like the finger shoe or section *f*. (Shown in detail in Figs. 18 to 20, inclusive.) In the machine here shown only twelve of said finger-shoes are used, each quarter of the ring having three sections, and if simple sections are to be used the number should be greatly increased—say at least doubled; but, as here shown, twelve serve a good purpose, because they are complex, inasmuch as with them I employ co-operating intervening finger plates or sections *g*, thus, in all, making substantially twenty-four sections, and I have successfully employed a much larger number of sections.

A finger-shoe section in Figs. 18 to 20, inclusive, is illustrated in longitudinal section, in top view and in rear end view. As clearly shown, its inner end is concave or in the arc of a circle, (or oval,) and is upwardly turned to afford a brim-folding surface, and its sides are inclined from end to end to correspond to the radiating lines of the particular portion of the folding-ring which it occupies. At each side it has a vertical web, and it also has a pair of vertical studs or posts, *f'*—one at each end—and on top of these there is secured a slotted plate, *f''*, wider than said studs, so that when the latter occupy a radial slot, *b'*, in the arched frame-plate *b* the finger-shoe sections will be supported by said frame-plate, and be free to slide longitudinally in said slot *b'*.

A finger plate or section, *g*, is shown in top view, rear end view, and longitudinal section in Figs. 21 to 23, inclusive, Sheet 5. They are composed, mainly, of thin sheet metal, and have an outline corresponding to that of the shoe-sections. At its center each finger-plate has a vertical longitudinal web, *g'*, having at each side thereof a laterally-projecting web, *g''*. Now, referring to Figs. 17 and 24, Sheet 5, it will be seen that between the wide radial open slots *b'* there are narrow radial grooves *g''*, which receive the webs *g'* on the finger-plates. As will be seen in Figs. 18 to 20, the finger-shoe sections have lateral recesses or openings *g''* in the webs at each side thereof, which receive in each case one of the laterally-projecting webs, *g''*, so that the several finger-shoes not only support the finger-plates, but they are so interlocked therewith that when said shoes are radially moved they carry with them the finger-plates. As has before been stated, said finger-plates are composed of thin sheet metal, and their inner ends, like the finger-shoes, are turned upwardly and for the same purpose, but they project beyond the shoes to the extent of the thickness of said plates, so that when the folding-ring is wholly contracted the curved inner ends of the finger-plates are in continuous contact, and overlie or cover the curved inner ends of the finger-shoes, as indicated at the upper portion of Fig. 17, so that when the folding-ring is fully expanded the inner ends of the shoes and finger-plates present a practically-continu-

ous oval outline, although as the ring is contracted the finger-plates gradually cover the shoes.

In order that the finger-shoes *f* may closely approach each other, each is laterally recessed at its side to accommodate the web *g'* on the adjacent finger-plates, as clearly indicated.

The means for causing the brim-folding ring to contract and expand may be widely varied without departure from certain features of my invention, the main point being to provide for uniform and simultaneous action at all parts of the ring.

As here shown, I employ mechanism somewhat similar to that heretofore used by me in my machines for blocking and stretching hats, as shown, described, and claimed in certain Letters Patent heretofore issued to me, but I herein claim said mechanism, in combination with the contractible and expansible brim-folding ring, whereby novel results are obtained which were not possible in any prior organization of mine wherein said patented mechanism has been employed.

Each finger-shoe is vibrated by means of a bell-crank lever, *h*, pivoted to a bracket, *h'*, bolted to the top frame-plate, *b*, and each lever *h* is connected to an annular cross-head, *D*, by means of a link, *h''*, and an adjustable pivot-bolt, *h'''*, all as clearly indicated in Fig. 7, Sheet 4, and in the detail views, Figs. 8 to 13, inclusive. The cross-head *D* is secured to the vertical sliding guide-rods *i*, and it is coupled at one side by a link, *i'*, to a lever-arm, *i''*, on the rock-shaft *E*, to which the hand-lever *F* is attached, another link, *i'''*, being connected therewith, as clearly indicated in Figs. 1, 2, and 4, whereby said cross-head is vertically reciprocated for contracting and expanding the brim-folding ring. In Fig. 1 the hat-bed is shown in its lowest position, ready to receive a block with a hat thereon, and the folding-ring is fully expanded, the hand-lever *F* being depressed. In Fig. 2 the working parts of the machine are in the same position as in Fig. 1; but a hat-block is in place with a hat thereon ready for the brim-curling operation. In Fig. 7 the hat bed and ring have been placed into working relations by depressing the foot-lever or treadle *B''*, and the hand-lever *F* has been partially raised and the brim-folding ring partially contracted. In Fig. 4, Sheet 3, the ring is shown fully contracted, the brim wholly folded, and receiving pressure applied at the treadle for thoroughly developing the folded edge of the interposed brim. It will of course be understood that the brims are first well heated, and that they are more or less cooled during the folding operation, but that the folded edge readily admits of the release of the folding guide-plate after the operation is concluded. The brims, having been thus folded and curled, are finished according to particular requirements, and I have devised a series of accompanying mechanism by which certain preceding trimming

operations are performed, and also such subsequent finishing operations as may be required can be rapidly and effectually accomplished.

5 It will be seen that the working parts of the machine may be variously organized without departure from certain portions of my invention—as, for instance, the brim-folding ring and the hat-bed may be reversed in their positions—and I have, as hereinbefore indicated, organized one form of machine in which the folding-ring is mounted upon a hat-bed, and wherein certain additional novel features are involved, which will be made the subject of a 10 separate application for Letters Patent.

15 While I find that the foot-lever and hand-lever are ample for profitably operating the machine, it is obvious that motive power may be applied for imparting motions corresponding to those due to the movements of said levers without departure from certain features of my invention.

Having described my invention, I claim as new and desire to secure by Letters Patent—

20 1. An expansible and contractible brim-folding ring, each quarter of which is composed of several radially-movable segmental sections each having a brim-folding edge at its inner end, substantially as described, whereby in 25 moving inwardly the folding-edge of each section will wholly act upon the edge of a brim, substantially at right angles to or crossing the peripheral line of the brim of a hat, and in radial lines, substantially as set forth.

30 2. An expansible and contractible brim-folding ring embodying two connected and co-operating series of radially-movable segmental sections, substantially as described.

35 3. An expansible and contractible oval brim-folding ring embodying segmental sections, which are provided with upwardly-turned folding-edges at their inner ends, and are adapted to be moved in lines radiating from two or more interior points, substantially as 40 described.

45 4. An expansible and contractible oval brim-folding ring embodying two connected and co-operating series of segmental sections, movable in lines radiating from two or more interior central points, substantially as described.

50 5. The combination, substantially as hereinbefore described, of a contractible and expansible

55 brim-folding ring, an annular brim-folding guide-plate, a hat-bed for supporting a hat-brim with said guide-plate pressed thereon, and means, substantially as described, for radially expanding and contracting said ring, and, after contraction, for forcing said bed and ring toward each other, and thereby compressing the interposed portions of the edge of a 60 hat-brim, as set forth.

6. The combination, substantially as hereinbefore described, of the expansible and contractible brim-folding ring, the hat-supporting bed, means, substantially as described, for 65 moving the bed and the ring into co-operative relations and for operating the ring, the brim-lifting annular plate mounted on said bed, and the annular guide-plate smaller than said lifting-plate.

7. The combination, with the brim-folding ring, the guide-plate, and the lifting-plate, of the hat-bed, the hat-block, the vertically-reciprocating spindle, and the treadle levers and links, substantially as described.

75 8. The combination of the expansible and contractible brim-folding ring, the series of bell-crank levers coupled thereto, and the vertically-reciprocating cross-head linked to said levers, substantially as described.

80 9. The combination, with an expansible and contractible oval brim-folding ring, of a hat-block, and means, substantially as described, for centering said block and accurately locating the front and rear portions of a hat-brim 85 in said ring, as set forth.

90 10. The combination, substantially as described, of the hat-bed and oval brim-folding ring, of the oval hat-block, the oval annular folding guide-plate, the oval annular lifting-plate, and means, substantially as described, for centering said block and plates, and for accurately mounting them in working position, as set forth.

95 11. The combination of the folding guide-plate, the oval hub on which it is mounted, and the irregularly-located dowel-pins and holes by which the plate is accurately mounted on said hub, substantially as described.

RUDOLF EICKEMEYER.
